(57) **CLAIM**

The ornamental design for the round firepit table, as shown and described.

DESCRIPTION

FIG. 1 is a perspective view of the round firepit table; FIG. 2 is a front elevation view of the round firepit table; FIG. 3 is a back side elevation view of the round firepit table; FIG. 4 is a left side elevation view of the round firepit table; FIG. 5 is a right side elevation view of the round firepit table; FIG. 6 is a top plan view of the round firepit table; FIG. 7 is a bottom plan view of the round firepit table; and, FIG. 8 is an exploded prospective view showing the assembly elements of the round firepit table illustrated in FIG. 1. The broken lines show portions of the round firepit table that form no part of the claimed design.

1 Claim, 6 Drawing Sheets
